US00D800660S

(12) **United States Design Patent** (10) **Patent No.:** **US D800,660 S**
(45) **Date of Patent:** **** Oct. 24, 2017**

(54) **FIBER OPTIC CONNECTOR**

(71) Applicant: **CORNING OPTICAL COMMUNICATIONS LLC**, Hickory, NC (US)

(72) Inventors: **Michael de Jong**, Colleyville, TX (US); **Alyson Paige Moore**, Newton, NC (US); **Brian Keith Rhoney**, Hickory, NC (US); **Carol Lee Buhrmaster Sparks**, Hickory, NC (US)

(73) Assignee: **CORNING OPTICAL COMMUNICATIONS LLC**, Hickory, NC (US)

(**) Term: **15 Years**

(21) Appl. No.: **29/529,307**

(22) Filed: **Jun. 5, 2015**

(51) LOC (10) Cl. **13-03**

(52) U.S. Cl.

(57) **CLAIM**

The design for a fiber optic connector, as shown and described.

DESCRIPTION

FIG. 1 is a perspective view of a fiber optic connector according to a first embodiment.

FIG. 2 is a top plan view of the fiber optic connector of FIG. 1.

FIG. 3 is a bottom view of the fiber optic connector of FIG. 1.

FIG. 4 is a left side elevation view of the fiber optic connector of FIG. 1.

FIG. 5 is a right side elevation view of the fiber optic connector of FIG. 1.

FIG. 6 is a back side elevation view of the fiber optic connector of FIG. 1; and,

FIG. 7 is a front side elevation view of the fiber optic connector of FIG. 1.

The broken dash-dot broken line portion of the figure drawings is included to show portions of the article that form no part of the claimed design. The dash-dot broken line

(Continued)

portion of the figure drawings is included to show the boundary of the claim and form no part of the claimed design.

1 Claim, 6 Drawing Sheets
